Primary Examiner — Keli L Hill(74) *Attorney, Agent, or Firm* — Fish & Richardson P.C.**CLAIM**

The ornamental design for a smart payment speaker, substantially as shown and described.

DESCRIPTION

FIG. 1 is a front perspective view of smart payment speaker, showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating portions of the smart payment speaker that form no part of the claim.
